61

CEMENT GUN NOZZLE

Application filed December 31, 1929. Serial No. 417,648.

62

This invention relates to cement gun nozzles and deals with the deposition of particles of a hydrated concrete mixture upon a surface or in forms by means of air pressure.

5 In applying cement or "gunite" by pneumatic means it is well known that a certain amount of rebound of the particles takes place as the particles are deposited and that the quantity of rebound ranges from a small 55
10 percentage to a high percentage of the total material conveyed, depending largely upon the nature of the product desired.

The term "rebound", as used in this connection, includes the particles reflected from 15 a depositing surface by the incident velocity of said particles, and also those particles swept from the surface by the force of the air transporting medium after it has left the nozzle orifice. This latter action may be 20 termed "air erosion", and is the primary subject matter of this invention.

In practice, it has been found that air erosion is highly objectionable in depositing cementitious materials especially in close 25 quarters such as trenches, molds, concrete forms, closed chambers, etc. Certain cases have arisen where eddy currents and counter currents have absolutely prevented the depositing of material. It is obvious, therefore, 30 that if the air transporting medium be separated from the material and diverted after it has performed its useful work but before it reaches the depositing surface that particles already deposited will remain in place 35 that otherwise would be swept from the surface by the blasting of the air. This invention purports to deal with this aspect of depositing cementitious materials by means 40 of cement gun equipment and provides a nozzle having means for deflecting the bulk of the air transporting agency in a manner that it will not appreciably erode the surface of deposition.

The principle involved in this invention is 45 based upon the theory that if compressed air is conveying material through a conduit, the air force of pressure takes advantage of every opportunity to expand and if an opportunity is afforded to expand along the radius of the cross-section, such expansion

may be made to take place gradually without materially altering the direction of the flow of the particles of conveyed material. To accomplish this, I have formed a nozzle embodying the principle of a tromba, or a 55 trumpet-shaped nozzle, which deflects a large amount of the air at the tip of the nozzle. The arrangement thus provided allows an expansion of the air transversely to the direction of the flow of material and changes 60 the direction of the flow of the air but does not appreciably affect the direction of the flow of the particles of material. In other words, the arrangement provides a nozzle 65 wherein the particles are projected in substantially a cylindroidal form while the air transporting medium is deflected at the tip of the nozzle substantially at right angles to the flow of the particles.

The primary object of this invention, therefore, becomes to provide a nozzle for use with 70 cement gun equipment having means in the nozzle for deflecting the air before it comes in contact with the surface upon which the particles are deposited. It is thus clear that 75 by deflecting the air, the eroding action of the air is obviated which is the principal benefit sought in this invention.

In a companion application, Serial No. 417,467, filed Dec. 30, 1929, I have shown a 80 nozzle having means therein for altering the ballistic properties of the particles of a projected mixture by means of an obstruction placed in the path of the flowing particles. 85 This arrangement causes a disturbance amongst the particles that reduces a large amount of kinetic energy of the particles into frictional heat and ineffective work.

It is evident that a combination of the 90 principles of obstructing the flow of the particles and the principle of deflecting the air current away from the surface of deposition may be combined. In this case, a modified form of nozzle is provided that is highly 95 useful for depositing material in close quarters where the eroding action of the air is objectionable and where a deposited product of low density is required. Other objects and advantages will become apparent 100

upon a detailed description when read in conjunction with the drawing in which

Fig. 1 is an elevation partly in section showing the principle employed in deflecting the air at the tip of the nozzle;

Fig. 2 is an elevation taken on the line 2—2 of Fig. 1;

Fig. 3 is an elevation partly in section of a combination nozzle involving the principle of deflecting the air and the principle of obstructing the flow of the particles; and

Fig. 4 is an elevation taken on the line 4—4 of Fig. 3.

In the drawing, wherein I have shown the principle of my invention somewhat diagrammatically, I have illustrated a nozzle designated at A suitably attached to a water ring B, which in turn is mounted upon the end of the material conveying hose C. As shown, the nozzle A is formed with outwardly flaring walls 11 which terminate in an orifice 10 of larger diameter than the base of the nozzle. This structure is recognized as a tromba and is known to operate as a means of deflecting elastic fluids passing therethrough substantially in the direction shown by the arrows 12. In this particular connection, the tromba shaped nozzle operates as a means of deflecting the air transporting medium in a similar manner and the air follows the direction of the arrows 12 while the sand particles having a greater mass and a high velocity continue to flow in an almost unaltered course and follow the direction of the arrow indicated at 13. This arrangement is appreciated as providing a nozzle wherein the propelling medium, i. e., the air is deflected at the nozzle orifice and, consequently, does not reach the depositing surface to erode particles of material therefrom. The result is a practical elimination of air "erosion". A nozzle of this type deposits a dense product and is particularly useful in placing concrete in molds, concrete forms, etc., or in any place where confined space is apt to set up eddy currents and counter currents by released air. This nozzle has been found upon experimentation to be capable of depositing "gunite" in the bottom of forms which could not be reached with the ordinary nozzle.

In Fig. 3, I have shown my nozzle A having substantially the same shape as in Fig. 1. In this instance the nozzle A is similarly connected to a water ring B which is mounted in the usual manner upon the material conveying hose C. In this arrangement I have introduced a means for obstructing the normal flow of the sand particles and of reducing the velocity of the particles. The means in this instance comprises an obstructing element E which is supported upon vane members 17 mounted within the nozzle and arranged directly in the path of the flow of the particles which, by impacting thereagainst,

are deflected upon the arrows indicated 14. The air, as in Fig. 1, is deflected in the direction indicated by the arrows 12 and passes through the openings 15 which are provided around the periphery of the tromba-shaped nozzle A. For the purpose of confining the deflected particles to a restricted area of deposition, a sleeve 16 is incorporated beyond the tip of the nozzle A and operates to further reduce the velocity of the particles by a continued series of impactings and deflections. The introduction of this feature will be readily recognized as a means of further reducing the velocity of the particles of sand and when taken in conjunction with the means of deflecting the air propulsion means, will be appreciated as providing a nozzle characterized by having proper qualifications for reducing the velocity of the sand particles before being deposited upon a surface which greatly reduces the rebound of the particles together with the added advantage of preventing the air from sweeping the zone of deposition and dislodging particles already deposited. This type of nozzle has been found highly successful for reducing the air erosion and the rebounding of particles due to excessive incident velocity.

Although I have shown a diagrammatic form of nozzle involving my invention, I intend this disclosure to include all forms that come within the scope of the invention as described in the specification and expressed in the appending claims.

I claim as my invention:

1. A nozzle of the character described comprising: a casing adapted to be mounted upon a material conveying conduit, said casing being tromba shaped; a particle obstructing element mounted in the orifice of said nozzle; and a sleeve mounted upon said casing beyond the orifice of said tromba shaped nozzle.

2. In a device of the character described, a nozzle, an obstructing element in said nozzle and a sleeve mounted on said nozzle spaced apart from the end of said nozzle.

3. In an air actuated material conveying element, a distributing member having openings in its walls adjacent the discharge end of the member, and a material obstructing element in said member centrally disposed therein.

4. In a device of the character described, a tromba shaped nozzle, an obstructing element in said nozzle centrally disposed therein, and a material directing member mounted on said nozzle spaced apart from the end of the nozzle.

In testimony whereof, I have hereunto set my hand at Los Angeles, California, this 18th day of December, 1929.

JOHN T. VAWTER.
